Folsom & Hayden,

Washing Machine,

Patented Dec. 17, 1805.

- Sellers Patent Applied Dec. 17, 1805.

The Tubular referred to in these Letters Patent and making part of the same containing a description in the words of the said William Johnson Wilson and John Hayden of their invention for washing, rinsing and airing clothes.

2 pgs

This Machine consists of two horizontal gates within a Box or Tub the base ^{under the upper one} and front. The movable gate is carried up and down by a lever purchased which is placed on a post fastened to the side of the Tub, about four feet in height from the floor and bending over at top within eight inches of the center of the Tub. This gate has a post fastened to the two opposite sides of it which is in grooves made in the Tub. They are connected ... at top by a cross bar. From the middle of this bar goes down into the end of the lever and is there fastened by a bolt. To this gate a strip of coarse cloth eight inches wide is ... fastened around near the edge and held up by strings looped outside of the Tub. This prevents the clothes to be washed (which are laid promiscuously within this Box on this gate) from coming to any harm. The upper gate is made to go in very largely and is placed so as to give the lower one room to play up and down from five to eight inches according to the quantity of clothes put in, this has two short posts on its sides and is fastened to the Tub by bolts.

These gates are made of two pieces of wood about an inch apart. The ^{top} ^{is made} box is made two feet in diameter, or less, for small families proportioned in height to width to make it a convenient washing Tub with a top on the side and standing on legs projecting to make it steady, and if shallow it requires a cover to lay on.

Upon the same principle two pair of gates may be made to work in a Box separated by a partition, and moved by a pendulum. N.B. Great care must be taken to make the Box or tub true inside, and of wood that will not shrink and settle as little as possible. Also the movable gate which may sometimes require work on leather around the edge to make it true particularly if made circular.
